DESIGN FOR A POCKET KNIFE

Said Ahmid, Dearborn, Mich.

Application August 18, 1938, Serial No. 79,431

Term of patent 14 years

To all whom it may concern:

Be it known that I, Said Ahmid, a citizen of Syria and Lebanon, residing at Dearborn, in the county of Wayne and State of Michigan, have invented a new, original, and ornamental Design for a Pocket Knife, of which the following is a specification, reference being had to the accompanying drawing, forming a part thereof, and in which,

Fig. 1 is a side elevational view of a pocket knife showing my new design.

Fig. 2 is a top plan view.

Fig. 3 is a bottom plan view.

Fig. 4 is a front elevational view.

What I claim is:

The ornamental design for a pocket knife, as shown.

SAID AHMID.
